US00D755669S

(12) **United States Design Patent**
Greczanik et al.

(10) **Patent No.:** US D755,669 S
(45) **Date of Patent:** ** May 10, 2016

(54) **PLAQUE AWARD**

(71) Applicants: **Vincent Greczanik**, Norton, OH (US);
Mike Oister, Moon Township, PA (US);
Scott Vollmer, Akron, OH (US)

(72) Inventors: **Vincent Greczanik**, Norton, OH (US);
Mike Oister, Moon Township, PA (US);
Scott Vollmer, Akron, OH (US)

(73) Assignee: **Invent Now, Inc.**, North Canton, OH (US)

(**) Term: **14 Years**

(21) Appl. No.: **29/491,056**

(22) Filed: **May 16, 2014**

(51) LOC (10) Cl. **11-02**

(52) U.S. Cl.
USPC **D11/132**
